UNITED STATES PATENT OFFICE

ISRAEL P. PEARLMAN, OF PROVIDENCE, RHODE ISLAND

DESIGN FOR A STORE FRONT

Application filed January 30, 1929. Serial No. 29,843. Term of patent 14 years.

To all whom it may concern:

Be it known that ISRAEL P. PEARLMAN, a citizen of the United States, residing at Providence, in the county of Providence and State of Rhode Island, has invented a new, original, and ornamental Design for a Store Front, of which the following is a specification, reference being had to the accompanying drawing, forming a part thereof,

The figure is a perspective front view of a store front embodying my new design.

I claim:

The ornamental design for a store front substantially as shown.

In testimony whereof I affix my signature.

ISRAEL P. PEARLMAN,
